UNITED STATES PATENT OFFICE.

HARRIE A. BALLARD, OF ASHLAND, MASSACHUSETTS, ASSIGNOR, BY MESNE ASSIGNMENTS, TO THE BOYLSTON MANUFACTURING COMPANY, OF BOSTON, MASSACHUSETTS, A CORPORATION OF NEW JERSEY.

CHAIN-STITCH SHOE-SEWING MACHINE.

1,117,304.

Specification of Letters Patent. Patented Nov. 17, 1914.

Application filed January 24, 1905, Serial No. 242,489. Renewed June 1, 1910. Serial No. 564,456.

To all whom it may concern:

Be it known that I, HARRIE A. BALLARD, of Ashland, in the county of Norfolk and State of Massachusetts, have invented certain new and useful Improvements in Chain-Stitch Shoe-Sewing Machines, of which the following is a specification.

This invention has relation to chain-stitch shoe-sewing machines and deals particularly with the looper mechanism and needle-actuating mechanism employed in that type of machines.

The primary object of the present invention is to provide certain improvements in the looper mechanism for the purpose of laying a loop of needle thread in the barb of the needle in such manner that it is substantially locked therein, or prevented from being dislocated or dislodged from the needle. This is accomplished in the present instance by causing the delivery end of the looper to describe an orbit around the needle of more than 360° , so that one bight of the loop will lie upon and lock the other bight of the loop as the needle is withdrawn through the work. Preferably the delivery end of the looper travels an acute path of approximately 540° . That is, it completes a circle or orbit, and a half of another one. Thus the thread laid around the needle, leaving the previous stitch, passes to the needle, thence around the needle, and extends away therefrom in the same general direction to the delivery end of the looper. As the needle is withdrawn, the loop forms a Blackwall hitch about the needle, and the end of the loop which extends to the work lies upon and locks the supply end.

The particular mechanism, which I have illustrated as embodying the invention, consists of a looper which is rotatable about a fixed axis with an eccentric nose or delivery end, and power-transmitting mechanism by which it is rotated in one direction through an orbit of more than 360° , and then, after the needle has drawn the loop into the work, is rotated reversely through an arc equal to its first movement less 360° , so as to bring it to its initial starting point ready for the next operation.

It is evident that the particular mechanism, which I have illustrated and described,

may be varied, and a wide range of equivalents therefor employed without departing from the spirit and scope of the invention.

Another object of the invention is to simplify and reduce the bulk of the needle-actuating mechanism. Instead of the commonly used cam-actuated lever for oscillating the needle, the present invention comprises an eccentric and eccentric-rod connected at both ends by ball-joints. By reason of this construction, the eccentric-rod swings laterally with the needle-carrier when the latter is reciprocated from side to side to feed the work. In machines heretofore employed, the needle-oscillating member has been incapable of lateral motion, necessitating a sliding connection between it and the needle-carrier.

Other features of construction are illustrated upon the accompanying drawings, and described in the following specification.

Of the drawings:—Figure 1 is a front elevation of a chain-stitch shoe-sewing machine embodying the features of the invention. Fig. 2 is a vertical section on the line 2—2 of Fig. 1, and indicated by an arrow. Fig. 3 is a section on the line 3—3 of Fig. 2. Figs. 4 to 7 inclusive show various positions of the gears which actuate the looper. Fig. 8 shows a development of the face of the looper driving gear. Fig. 9 shows a development of the face of the driven gear. Fig. 10 represents somewhat conventionally a needle with the bights of the loop crossed to form a Blackwall hitch and lock the bight which leads to the thread supply.

The same reference characters indicate the same parts wherever they occur.

As shown in Fig. 1, the machine comprises a head 10 adjustably mounted upon a suitable base or standard 11 and secured thereto at any desired angle by means of a clamping bolt 12. The head comprises suitable upright portions 13 13, one at each side thereof, in which are formed suitable bearings for a main cam-shaft 14, on which are mounted the actuating members for the various mechanisms hereinafter described.

15 is the needle which is of the hooked oscillatory type and suitably secured in a needle-carrier 16 mounted upon a stud 17 projecting from an arm 18 formed on the feed-

ing carriage 19. The said carriage is held and adapted to reciprocate in laterally-extending guides 20 on the head 10, for the purpose of feeding the work step by step. The carriage is reciprocated by a lever 21 pivoted upon a fixed stud 22 and having on one end a trundle-roll 23 which occupies a cam-groove 24, formed in a cylindrical member 25 mounted upon the shaft 14. The other end of the lever 21 has a radially extending slot 26 in which is adjustably clamped a stud 27. Said stud projects into a slot 28 formed in a portion of the carriage, and substantially parallel to the slot 26. It will be seen therefore that the carriage 19 and needle-carrier 16 reciprocate laterally as a unit, by reason of the actuation of the lever 21 by the cam 24.

30 is an eccentric mounted on the shaft 14. Said eccentric is formed as the central zone of a sphere, having a convex face, and a suitable hub to increase its bearing on the shaft. A split eccentric strap 31 having an arm or rod 32 is clamped in the usual way upon the eccentric. The inner face of the strap is concaved in conformity with the convex surface of the eccentric, thus providing a universal joint about which the rod 32 may swing. The forward end of the rod is provided with a split socket 33 and is connected by a ball-headed stud 34 to an arm 35 on the needle-carrier 16. The ball and socket 34 33, in addition to providing means whereby the rod 32 may oscillate the needle-carrier, permit a lateral movement of the carrier relatively to the rod. It will be seen, from the foregoing description, that rotation of the eccentric 30 causes the eccentric-rod 32 to oscillate the needle-carrier, and that the needle-carrier may be reciprocated laterally by the cam 24, without in any way interfering with the action of the eccentric-rod. In order to prevent the eccentric-rod from 45 rocking on an axis intersecting the centers of the eccentric 30 and stud 34, a peripheral groove 36 is turned in the eccentric and dowel-pins 37 are set into opposite sides of the strap 31 so as to project into the groove 50 at right angles to said axis. The pins 37 do not interfere with the rotation of the eccentric, but they maintain it in an upright position, (see Figs. 2 and 3).

The looper mechanism is mounted in a bracket or arm 40 at the front of the head 10. The looper, indicated at 41, is formed on or affixed to the lower end of a hollow shaft or tube 42 rotatably mounted in a bearing formed in said bracket. Said shaft 55 is slightly inclined from a vertical position, so that its axis may be tangential to the arc of the needle 15, and it is hollow for the purpose of allowing the thread *t* to pass therethrough. The delivery end of 60 the looper is provided with an eccentric hol-

low nose 43 which is adapted to encircle the needle. The looper, between the nose and the shaft or tube 42, is cut away so as to provide a free space for the point of the needle while the nose lays the thread about 70 the barb of the needle. Suitable take-up and locking mechanisms for the thread *t* are shown, but as they form no part of the invention, description is unnecessary.

A spiral gear 44 is affixed to the tube 42 75 and intermeshes with a spiral gear 45 affixed to a shaft 46 of which one end is journaled in the bracket 40 and the other end in a bracket 47, located beneath the main shaft 14. The ratio of the gear 45 to the gear 44 80 is as two is to one, for a purpose hereinafter described. To the rear end of the shaft 46 is affixed a mutilated spiral gear 48 which intermeshes with and is driven by a mutilated spiral gear 50 affixed to the main shaft 85 14. The gear 50 which rotates continuously with the shaft 14 is adapted to impart to the gear 48 and consequently to the gear 45 an intermittent motion of which each cycle comprises a dwell, a rotation of predetermined extent in one direction, a second dwell and a partial counter rotation. To be specific, each forward rotation of the shaft 46 and gears thereon covers 270 degrees of a revolution and each counter rotation covers 90 degrees. This is converted by the gears 44 and 45, already described, into one and one-half revolutions of forward rotation of the looper, and one-half revolution of counter rotation thereof. It will be understood, however, that the invention is not limited to the exact movements as described, but that the several gears may be rotated more or less in either direction to suit prevailing conditions, without departing from 105 the spirit of the invention. This action of the looper results as follows. The thread is carried by the nose or delivery end of the looper, from the end of the preceding loop, around the needle, and thence beyond the 110 needle away from the preceding loop. The looper remains stationary as the needle withdraws through the work, one bight of the thread of the loop on the needle lying across and locking the other bight of the needle to 115 form what, in nautical knots, is termed a Blackwall hitch. As soon as the loop has been withdrawn through the work, the delivery end or nose of the looper is reversely 120 moved to bring it to its original starting point, ready to lay another loop upon the needle after the needle has again penetrated the work (and fed it, if a needle feed be employed, as herein described).

By reference to Figs. 5, 6, 7 and 9, it 125 will be seen that the gear 48 is composed of four quadrants or segments *a a* and *b b*, which are separated by slots or grooves *c c* and *d d*. The segments *a a* are composed of simple spiral teeth, and the segments *b b* 130

are composed of square pyramid-shaped teeth arranged diagonally. Said diagonal teeth are the result of cutting left-hand spiral teeth over right-hand spiral teeth, 5 or vice versa. It will be seen, therefore, that the entire gear 48 is adapted to intermesh with a right-hand spiral driving gear, but that the segments *b b* are adapted to intermesh with either right or left-hand spiral 10 teeth.

The gear 50 comprises a segment A of right-hand spiral teeth, a segment B of left-hand spiral teeth, a peripheral fin or flange C connecting said segments on one side and 15 a similar fin D connecting them on the other side. The segment A is adapted to intermesh with any or all of the teeth of the gear 48, but the segment B is adapted to intermesh only with the segments *b b* of said 20 gear. According to the formation shown the fin C is caused to enter either of the grooves *c c* in the gear 48, and the fin D is caused to enter either of the grooves *d d* between the passage of the segments A and B, 25 to hold said gear against undue rotation at predetermined times.

It will be observed that the gear 48 has the equivalent of twelve teeth around its periphery and that the segment A has nine 30 teeth and the segment B three teeth. Referring to Figs. 4, 5 and 7, it will be seen that the gear 48 is locked by the presence of the fin C in one of the grooves *c*. As the segment A enters into the teeth of the gear 48, 35 the foremost tooth of said segment engages the nearest tooth of the segment *a*, while at the same time the nose of the next tooth of the segment A enters between the teeth of the segment *b*. Continued rotation of 40 the gear 50 causes the segment A to impart to the gear 48 forward rotation of 270 degrees, as indicated by the broken line *x* in Fig. 5. During this period of rotation, the segment A engages a segment *b*, a segment *a*, 45 and a segment *b*, in the order named. As the segment A leaves the gear 48, the fin D enters one of the grooves *d* and so locks the gear 48 while the segment B approaches. (See Fig. 6). As the segment B enters, the 50 foremost tooth thereof engages the nearest tooth of the segment *a*, and the nose of the next tooth of the segment B enters between the teeth of the segment *b*. The passage of the segment B imparts to the gear 48 a 55 counter rotation of 90 degrees, as indicated by the broken line *y* in Figs. 5 and 6, leaving said gear just 180 degrees in advance of its original position. The foregoing detailed description embraces one complete cycle of movements of the looper mechanism.

The mechanical motion, comprising the two gears 48 and 50, is set forth and claimed in my co-pending application, Serial No. 242,490, filed concurrently herewith, and is 60 not specifically claimed herein.

Having thus explained the nature of the invention, and described a way of constructing and using the same, although without attempting to set forth all of the forms in which it may be made, or all of the modes 70 of its use, I declare that what I claim is:

1. A shoe-sewing machine comprising a four-motion work-feeding member, means for reciprocating said member to impart feeding movements thereto, and means for 75 otherwise reciprocating said member to move the same to and from the work, the latter means comprising an eccentric having a spherical surface and a circular groove therein arranged in a plane transverse to 80 the axis of rotation, an eccentric strap coacting with said eccentric and having universal joint connection with said feeding member, and a pivot member connecting said eccentric and strap, said pivot member 85 being arranged to traverse said groove, the axis of said pivot member being at right angles to a line intersecting said universal joint connection and the center of said eccentric. 90

2. A shoe-sewing machine comprising a four-motion, work-feeding member, means for reciprocating said member to impart feeding movements thereto, and means for otherwise reciprocating said member to 95 move the same to and from the work, the latter means comprising an eccentric having a spherical surface and a circular groove therein arranged in a plane transverse to the axis of rotation, an eccentric strap having a spherical socket coacting with said eccentric, ball and socket connection between said strap and said work-feeding member, and a pivot member connecting said eccentric and strap, said pivot member being arranged to traverse said groove, the axis of 100 said pivot member being at right angles to a line intersecting the center of said ball and socket connection and the center of said eccentric. 105

3. A chain-stitch shoe-sewing machine comprising an axially movable oscillatory needle, means for moving said needle axially, a member rigidly connected to said needle and having a spherical portion, a 110 rotatory axially immovable member on an axis parallel to that of said needle, and having a spherical surface eccentric to its axis of rotation, a bodily movable connecting rod having a spherical socket for each 115 of said spherical members, an equatorial groove in the surface of said rotatory member, and diametrically opposite trunnions projecting from said rod into said groove on an axis transverse to a line intersecting 120 the center of said sockets. 125

4. A shoe-sewing machine comprising a needle, a tubular looper having an eccentric nose, a fixed bearing for said looper, and means arranged to rotate said looper about 130

its axis alternately in opposite directions to cause a thread-laying movement of more than one rotation and less than two rotations, and a reverse movement to the starting position of said thread-laying movement.

In testimony whereof I have affixed my signature, in presence of two witnesses.

HARRIE A. BALLARD.
